UNITED STATES PATENT OFFICE.

JOSEPH MOSES WARD KITCHEN, OF EAST ORANGE, NEW JERSEY.

BOTTLE-CLOSURE.

1,224,649.

Specification of Letters Patent.

Patented May 1, 1917.

Application filed March 8, 1915. Serial No. 11,669.

To all whom it may concern:

Be it known that I, JOSEPH MOSES WARD KITCHEN, a citizen of the United States, residing in the city of East Orange, county of 5 Essex, State of New Jersey, have invented new and useful Improvements in Bottle-Closures, of which the following is a specification.

The object of the invention is through 10 sanitary provision, to make available for practical use as a sanitary milk bottle, the old insanitary style glass bottle of which many millions are in the hands of milk dealers, and which it may economically be desirable 15 to use until it becomes possible to secure a better type of bottle such as I describe in my copending applications, Sr. No. 810,105, and Sr. No. 874,385.

In the accompanying drawings, Figure 1 20 represents in vertical section, the lip and adjacent parts of the old style milk bottle. Fig. 2 represents in vertical section, the ordinary paper pulp sealing disk that is used to close the mouth of the old bottle, it being jammed into the recess seat *b*, and held in place by 25 centrifugally exerted pressure. In Fig. 3, an improved sealing disk cap is shown in vertical section, having in combination, a jamming disk *B*¹, the upper disk *B*, which rests on the upper horizontal part of the bottle lip, and intermediate disks *B*²; the various disks being wired together. Fig. 4 represents 30 a vertical section, the superimposing metal jam-cap *C*, which is pressed down and jammed over the bottle lip, covering and protecting the lip and the paper disk seal that may be used, from infection by germs. The metal cap *C* has the horizontal crown sheet part *C*¹, the inclined-from-the-vertical 35 skirt portion sides *C*², and the rolled rim *C*³. Fig. 5 represents a modified form of superimposing cap, in which a portion of the skirt part is made vertical, instead of being inclined from the vertical as in Fig. 4. Fig. 6 40 represents in vertical section, the assembled elements of my bottle closure coöperatively in position. All the elements of this closure are structurally old; hence, the invention consists in combining the several elements 45 coöperatively in a manner to secure a new result of value from a sanitary point of view.

When the metal cap *C* is pressed down upon and around the bottle lip, the inclined side *C*² becomes jammed against the most external tuberosity of the bottle lip (see *a*—*a* Fig. 1), and is held in place by the power of a centripetally exerted force and the friction consequent to the jamming together of the glass and metal surfaces at the level *a*—*a*. The rolled rim *C*³ of the cap prevents cutting 60 of the hand in removing the metal cap from the bottle lip. The vertical height of the metal cap provides for a confined amount of air under the cap that through elastic pneumatic repulsion prevents an upwardly 65 moving accession of infecting air or water to the paper seal used, during the process of pasteurizing the contents of the bottle in the bottle. There are two seals formed in this closure. A conditional, partly air-tight 70 seal effected by the paper disk; and the conditional seal formed at the level *a*—*a* by the contact of the metal and glass at the level *a*—*a*, which latter conditional seal prevents access of insects and dust to the parts of the 75 bottle lip above that lower seal, as well as to the paper closure disk used. In this form of closure, the pasteurizing performance can be conducted by either immersion, spraying or vaporization. The metal cap *C* is made 80 sufficiently strong to allow for piling cracked ice on the top of the bottle closure. It is a convenient cover for the bottle mouth during an intermittent use of the contents of the bottle, which prevents the falling of dust 85 into the bottle or absorption of odors by the contents of the bottle.

To prevent rusting of the base metal of the interior of the cap from abrasions, pin holes or cracks in its tinned coating, its surface may be wiped occasionally with sterilized butter, vaseline, or a neutral paraffin oil. The diameter of the metal cap is suited to the size of the bottle lip, and it is so gaged, that in adjusting the metal cap to its place, 90 an air space *D* is maintained between the crown sheet *C*¹ and the upper surface of the paper sealing disk. 95

What I claim as new is:

In a bottle closure, the combination of a 100 bottle lip having a recessed sealing seat in the interior of the upper part thereof, and an

outwardly projecting annulus of curvilinear cross-section at the upper portion, a compressible seal seated in said recess and frictionally retained therein, and a one-piece metal cap having a flaring flange and fitting over said annulus to form a conditional seal, said flange and lip being of such relative

size as to prevent the top of the metal cap from coming into contact with said lip or said seal.

JOSEPH MOSES WARD KITCHEN.
